UNITED STATES PATENT OFFICE

ALPHONSE D. WEIGOLT, OF CLEVELAND, OHIO, ASSIGNOR TO THE GOODYEAR TIRE & RUBBER COMPANY, OF AKRON, OHIO, A CORPORATION OF OHIO

DESIGN FOR A CORD TESTING MACHINE

Application filed July 6, 1932. Serial No. 44,271. Term of patent 14 years.

To all whom it may concern:

Be it known that I, ALPHONSE D. WEIGOLT, a citizen of the United States, residing at Cleveland, in the county of Cuyahoga and State of Ohio, have invented a new, original, and ornamental Design for a Cord Testing Machine, of which the following is a specification, reference being had to the accom-

panying drawing, forming a part hereof in which, the figure is a perspective view of a cord testing machine, showing my new design.

I claim:

The ornamental design for a cord testing machine, as shown.

ALPHONSE D. WEIGOLT.
